(57) **CLAIM**

The ornamental design for a heart-shaped grommet, as shown and described.

DESCRIPTION

FIG. 1 is a front elevational view of a heart-shaped grommet showing my new design;

FIG. 2 is a rear elevational view thereof;

FIG. 3 is a front perspective view thereof;

FIG. 4 is a side elevational view thereof, the opposite side being a mirror image;

FIG. 5 is a bottom end elevational view thereof, shown front down; and,

FIG. 6 is a top end elevational view thereof, shown back down.

The broken lines showing environment in FIG. 1 are for illustrative purposes only and form no part of the claimed design.
